UNITED STATES PATENT OFFICE.

HENRY PRICE BALL, OF PITTSFIELD, MASSACHUSETTS, ASSIGNOR TO GENERAL ELECTRIC COMPANY, A CORPORATION OF NEW YORK.

RESISTANCE ELEMENT.

1,149,173.

Specification of Letters Patent. Patented Aug. 10, 1915.

Original application filed August 6, 1909, Serial No. 511,521. Divided and this application filed April 9, 1914. Serial No. 830,595.

To all whom it may concern:

Be it known that I, HENRY PRICE BALL, a citizen of the United States, residing at Pittsfield, county of Berkshire, State of Massachusetts, have invented certain new and useful Improvements in Resistance Elements, of which the following is a specification.

My present invention relates to a resistance unit or element and the method of manufacturing the same and has for its object the provision of a simple and efficient unit which is well adapted for use in flat-irons or other heating devices.

This application is a division of my prior application, Serial No. 511,521, filed August 6, 1909. In that application I have disclosed a flatiron in which the resistance unit is cast in the body of the iron.

My present application relates to the form of resistance unit described in my prior application. The unit is formed of zigzag resistance conductors laid between strips of insulating material and inclosed in a flattened tube. Insulating members are provided to prevent the conductors from contacting with the tube and the tube is flattened so as to compress the members tightly.

In the accompanying drawings, Figure 1 is a sectional view of a flatiron embodying my invention; Fig. 2 is a plan view of the bottom portion of the iron; and Fig. 3 is a perspective view of the heating unit which is covered by my present invention.

Referring to the drawings, 10 represents the body portion having a heating unit 11 cast therein. This unit is formed of a flat strip and is cast on edge, that is, it stands in the body of the iron in a plane perpendicular to the plane of the iron and also in a plane perpendicular to the plane of greatest contraction in cooling. The unit is preferably looped or reflexed, as shown in Fig. 2, to enable as much of the unit as possible to run transversely to the longitudinal length of the iron, as I find the iron shrinks greater lengthwise than crosswise, and this subjects the sides of the unit to enormous pressure, when the cast iron bears down upon it. The reflexing also prevents any tendency on the part of the sides of the flattened tube to open up due to mechanical strain. It also locks the mica or other insulation inside the tube so that it cannot shift. The unit itself con-

sists of a zigzag resistance conductor 12, 55 which may be formed in any desired manner, as for instance, by punching it out of sheet metal. The material out of which this is formed is preferably of high resistance and non-oxidizable. I have found that the resistance metal disclosed in the patent to Dempster 901,428 is very suitable for this purpose. The resistance conductor is zigzagged so as to form a strip, and is laid between two strips of insulating material 13, such, for 60 instance, as mica, and insulating members 14, which may also be of mica, are secured between the sections of the conductor, as shown in Fig. 3. These insulating members are placed at intervals along the conductor 70 to prevent the conductor from contacting with the inclosing casing. The resistance conductor with its mica strips is then inclosed in a flat tube, as shown in Fig. 3. The tube is flattened to the form necessary, and 75 may then be further flattened so as to compress the members tightly.

While I have described my invention as embodied in concrete form for purposes of illustration, it should be understood that I 80 do not limit my invention thereto, since various modifications thereof will suggest themselves to those skilled in the art without departing from the spirit of my invention, the scope of which is set forth in the 85 annexed claims.

What I claim as new and desire to secure by Letters Patent of the United States, is:—

1. A resistance element comprising a heat-conducting sheath having a continuous unbroken outer surface and an insulated high resistance conductor maintained at a minimum thickness within said sheath by the walls thereof. 90

2. A resistance element comprising a heat-conducting sheath having a continuous unbroken outer surface and an insulated high resistance conducting ribbon inclosed within said sheath and maintained at a minimum 100 thickness by the walls thereof.

3. A resistance element comprising a heat-conducting sheath having a continuous unbroken outer surface and an insulated high resistance conducting ribbon having a plurality of lateral slots cut alternately in opposite edges to form a zig-zag current conducting path therethrough and maintained 105

under compression at a minimum thickness within said sheath.

4. The method of forming an electrical heater element which consists in threading an insulated conductor through a metal tube and then subjecting the assembled parts to high pressure.
5. The method of forming an electrical heater element which consists in threading an insulated conductor through a metal tube

and then applying sufficient pressure to said tube to reduce the same to a minimum thickness.

In witness whereof, I have hereunto set my hand this 4th day of April 1914.

HENRY PRICE BALL.
